UNITED STATES PATENT OFFICE.

DELBERT E. HOFFMAN, OF SHAW ISLAND, WASHINGTON.

CHANGE-SPEED GEARING FOR POWER PURSE-SEINE REELS.

1,201,466.

Specification of Letters Patent. Patented Oct. 17, 1916.

Application filed April 3, 1915. Serial No. 18,981.

To all whom it may concern:

Be it known that I, DELBERT E. HOFFMAN, a citizen of the United States of America, residing at Shaw Island, in the county 5 of San Juan and State of Washington, have invented certain new and useful Improvements in Change-Speed Gearing for Power Purse-Seine Reels, of which the following is a specification, reference being had there- 10 in to the accompanying drawing.

This invention relates to a mechanism for facilitating the changing of speed of power purse seine reels, and has for its object the production of a simple and efficient means 15 whereby the changing of the speed of the reel may be very quickly and efficiently obtained.

Another object of this invention is the production of a simple and efficient construction for facilitating the quick and efficient changing of the speed of the reel. 20

With these and other objects in view this invention consists of certain novel combinations, constructions, and arrangements of 25 parts as will be hereinafter fully described and claimed.

In the accompanying drawings: Figure 1 is a top plan view of the reel. Fig. 2 is an end elevation thereof, the support being 30 shown in section. Fig. 3 is an enlarged top plan view of the speed changing device. Fig. 4 is a detail perspective of the speed changing mechanism. Fig. 5 is a side elevation of the brake mechanism.

35 Referring to the drawings it will be seen that 1 designates the supporting platform which carries a king-swivel 2. This king-swivel 2 carries an enlarged bevel gear 3, which bevel gear meshes with a bevel gear 4 carried by the drive shaft 5 for the purpose of swinging the reel-carrying frame 6 to the desired position. A track 7 is carried by the supporting platform 1 for facilitating the turning of the reel-carrying frame 6.

45 The king-swivel 2 carries a bevel gear 10 at the top thereof which meshes with the bevel gear 11 carried by the transmission shaft 12. This transmission shaft 12 is supported upon the frame 6 in any suitable or 50 convenient manner and carries a plurality of speed gears 13 near one end thereof. The frame 6 carries a pair of transversely extending parallel tracks 14, which tracks are provided with longitudinally extending slots 55 15, and upon these tracks 14 is adapted to slide the shifting frame 16, the shifting

frame 16 being provided with depending bolts 17 for traveling in the slots 15. This shifting frame 16 is provided with a rearwardly extending ear 18, which ear is connected to a lever arm 19, and this lever arm 19 is in turn connected to a link 20, which link is secured to an operating lever 21 as illustrated in Fig. 2. The operating lever 21 is provided with a latch 22 for engaging 60 the quadrant 23 and holding the lever 21 in a set position. The quadrant 23 is provided with a plurality of notches 24 so spaced as to hold the shifting frame 16 in a predetermined shifted position according to each 65 notch.

A pair of links 25 are pivotally secured upon the shifting frame 16, and these links are connected to a gear shifting arm 26, which gear shifting arm 26 is provided with 70 a pair of laterally projecting spaced fingers 27, which fingers fit upon opposite sides of the changing gear 28 for moving the same laterally to be thrown into engagement with the respective speed gears 13. The gear 28 75 is keyed to the countershaft 29 so as to have free lateral sliding movement thereon. The arm 26 is connected to a link 30, which link is in turn connected to a pivoted bell crank lever 31 so as to allow the arm 26 to 80 be shifted laterally for moving the gear 28 to a position to be thrown into engagement with the desired speed gear 13.

85 It should be understood that when it is desired to shift or change the speed of the reel, that the gear 28 is moved out of engagement with one of the speed gears 13 and is then moved laterally to the desired position for engagement with the next or desired speed gear, whereupon the lever 21 90 is swung to the desired position for causing the latch 22 to engage the desired notch, whereby the shifting frame 16 will be moved to such a position as to cause the gear 28 to be thrown into direct contact with 95 one of the speed gears 13, thereby imparting rotary movement to the gear 28 and shaft 29. A sprocket wheel 32 is carried by the shaft 29, and this sprocket wheel receives a sprocket chain 33, which chain 33 passes over a sprocket wheel 34 carried by the shaft 35, which shaft 35 supports the reel hereinafter described. The shaft 35 is supported upon the end standards 36, and the shaft 35 also engages a plurality of end 100 plates 37, which end plates are secured to the end disks 38 of the reel. The disks 38 105

and plates 37 are connected by means of the longitudinally extending slats 39, which slats are braced intermediate their ends by means of the wheels 40. A brake lever 46 5 is pivotally mounted upon the reel-carrying frame 6 and carries a pivotally mounted brake shoe 47 for facilitating the throwing of the brake shoe 47 into engagement with one of the end disks 38.

Having thus described the invention what is claimed as new, is:—

1. A speed changing gearing especially adapted for use in connection with reels comprising a driving shaft, a plurality of 15 variable speed gears carried by said driving shaft, a plurality of track bars, a gear-carrying frame slidably mounted upon said track bars and capable of lateral movement relative to said driving shaft, said gear-carrying frame being substantially U-shaped, a journal box carried by each end of said frame, an auxiliary shaft carried by said sliding frame, a gear carried by said auxiliary shaft, means for shifting said gear 20 laterally for facilitating the engagement of said gear with said variable speed gears, a link engaging said sliding frame, and lever means engaging said link for facilitating the shifting of said sliding frame upon said 25 track bars.

2. A speed changing gearing especially adapted for use in connection with reels comprising a driving shaft, a plurality of 35 variable speed gears carried by said driving shaft, a plurality of track bars, a gear-carrying frame slidably mounted upon said track bars and capable of lateral movement relative to said driving shaft, said gear-carrying frame being substantially U-shaped, a 40 journal box carried by each end of said frame, an auxiliary shaft carried by said sliding frame, a gear carried by said auxiliary shaft, means for shifting said gear laterally for facilitating the engagement of 45 said gear with said variable speed gears, a link engaging said sliding frame, and manually operated lever means engaging said link for facilitating the shifting of said sliding frame upon said track bars.

3. A gear shifting device for use in connection with reels comprising a support, a main shaft, a plurality of variable speed gears carried by said main shaft, a plurality of track bars carried by said frame, a gear-carrying frame slidably mounted upon said 55 track bars, said gear-carrying frame comprising a pair of parallel arms, a journal box carried by each arm, an auxiliary shaft carried by said journal boxes, a gear carried by said auxiliary shaft, links pivotally connected to said journal boxes, a shifting bar connected to said links and provided with a pair of spaced laterally extending fingers fitting upon opposite sides of said last mentioned gear, and lever means engaging said 60 shifting bar for moving the same laterally and causing said last gear to be thrown into proper alignment with one of the selected variable speed gears.

4. A gear shifting device for use in connection with reels comprising a support, a main shaft, a plurality of variable speed gears carried by said main shaft, a plurality of track bars carried by said frame, a gear-carrying frame slidably mounted upon said 75 track bars, said gear-carrying frame comprising a pair of parallel arms, a journal box carried by each arm, an auxiliary shaft carried by said journal boxes, a gear carried by said auxiliary shaft, links pivotally 80 connected to said journal boxes, a shifting bar connected to said links and provided with a pair of spaced laterally extending fingers fitting upon opposite sides of said last mentioned gear, lever means engaging said 85 shifting bar for moving the same laterally and causing said last gear to be thrown into proper alignment with one of the selected variable speed gears, said tracks provided with longitudinally extending slots, and 90 bolts carried by said gear-carrying frame and working in said slots for controlling the distance of travel of said gear-carrying frame upon said track bars.

In testimony whereof I hereunto affix my 95 signature.

DELBERT E. HOFFMAN.
